(57) **CLAIM**

We claim the ornamental design for a stand for television, as shown and described.

DESCRIPTION

FIG. 1 is a front perspective view of a stand for television showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view thereof shown in an environment of use; and,

FIG. 9 is a rear perspective view of FIG. 8.

The evenly-spaced broken lines shown in FIGS. 1-7 illustrate portions of the stand for television that form no part of the claimed design. The evenly-spaced broken lines illustrating the television in FIGS. 8 and 9 are environment that form no part of the claimed design, while the remaining evenly-spaced broken lines in FIGS. 8 and 9 illustrate portions of the stand for television that form no part of the claimed design. The dot dash lines in FIGS. 1-6 and 9 represent an unclaimed boundary line and form no part of the claimed design.
